UNITED STATES PATENT OFFICE.

RICHARD M. SHAFFER, OF BALTIMORE, MARYLAND, ASSIGNOR OF ONE-FOURTH TO CHARLES B. MANN AND ONE-FOURTH TO CHARLES B. MANN, JR., BOTH OF BALTIMORE, MARYLAND.

AEROPLANE-PROPELLER.

1,338,874.

Specification of Letters Patent.

Patented May 4, 1920.

Application filed September 20, 1917. Serial No. 192,278.

To all whom it may concern:

Be it known that I, RICHARD M. SHAFFER, a citizen of the United States, residing at Baltimore, in the State of Maryland, have 5 invented certain new and useful Improvements in Aeroplane-Propellers, of which the following is a specification.

This invention relates to improvements in propellers for air-craft.

10 One object of the invention is to provide an improved construction of propeller in which the blades thereof are effectively braced against strains that tend to bend the same in a direction at right angles to their 15 flat faces and which are further braced against edgewise rearward strains or strains in a direction reverse to that in which the blades are revolving.

A further object of the invention is to 20 provide an improved construction of air-craft propeller employing a plurality of main blades and a bracing blade for each main blade,—the entering and trailing edges of the bracing blades being out of 25 alinement with the entering and trailing edges of the main blades.

A still further object of the invention is 30 to provide an improved construction of air-craft propeller employing main and bracing blades so arranged that the bracing blade has a position to lap the trailing edge of the main blade, and

35 A further object is to provide in an air-craft propeller a blade structure embodying a main and a bracing blade,—the bracing blade having its outer end connected to the outer end of the main blade and from said outer end the bracing blade extending away from the main blade and being non-parallel 40 therewith.

With the above, and other objects in view, the invention is illustrated in the accompanying drawing which latter, however, is in no way intended to define or limit the 45 scope of the invention, but has for its function, merely, to illustrate a form of structure embodying the inventive idea.

In the drawing,—

Figure 1, shows the propeller in rear elevation or as viewed from the rear side with respect to the direction in which it advances.

Fig. 2, illustrates the same in front elevation.

Fig. 3, shows the same in edge view.

Referring to the drawing the numeral 5, 55 designates a hub structure, in the present instance of tubular form but which may be of any desired form so far as the present invention is concerned. In this instance the hub is provided with two radially-extending flat plates 6, one diametrically opposite the other, and at slight incline with respect to the axis of the hub, for a purpose that will presently be explained.

In the present illustration the two main 65 blades 7 and 8, are shown as separate pieces of wood; the shape or outline of these wood blades may differ from that shown. As here shown the blades have narrow portions 70 9, near the hub which portions are lapped over or seated upon the flat metal plates 6, to which they are rigidly secured by screws or fastenings 10. It is common for two blades projecting oppositely from a hub to have one piece of wood extending from tip 75 to tip and to be built up of plies or laminations, which are thickest at the hub and said one piece to extend from the tip end of one blade to the tip end of the other blade,—a hub structure being fitted to such propeller 80 intermediate the two blades and the ends being thinnest. Blades of this structure may be utilized in connection with the bracing feature of my invention.

In carrying out my invention I provide a 85 hub having radially-extending supporting devices 11, which devices are spaced from and located at one side of the attaching means 6, for the main blades, as clearly shown in Fig. 3, of the drawing. In the 90 present instance these supporting devices 11, have the form of flat lugs or plates, which are located slightly to the rear of the plates 6, to which the main blades are attached, as readily seen in Figs. 2 and 3, of 95 the drawing, so that during the revolution of the propeller the supporting lugs or plates 11, will travel in a circular path just behind the radial flat plates 6. It is to be understood that the supporting devices need not 100 have the form of flat plates but may be otherwise formed.

The main feature of my invention lies in the provision of bracing devices for the main blades 7 and 8, of the propeller and 105 in the structure shown these bracing devices

have the form of propelling blades 12 and 13, respectively.

These bracing blades, have a comparatively straight entering edge 14, which, when compared with the direction of rotation of the propeller, has position to the rear of the entering edge 15, of the main blade which it braces, and the trailing edge 16, of each bracing blade projects rearwardly and beyond the trailing edge 17, of the main blade.

The bracing blades have their outer ends secured in bracing relation at the flat side and end of each main blade, a metal clip or other securing device 18, being employed to rigidly secure the two blade-ends in rigid relation. From the outer secured ends the bracing blades incline laterally and at the same time extend slightly to the rear of the main blade so each bracing blade 12 and 13, will form both a lateral brace and a circumferential brace for one main blade.

The inner end 19, of each bracing blade seats against the supporting device or plate 11, and is rigidly attached to the latter by means of fastening devices 20.

From the foregoing explanation it is to be understood that the bracing blades are located at the advancing side of the main blades so as to brace the outer thin ends of the blades at that side, and prevent said ends from bending forward as the result of their rearward thrust on the air in driving the craft forward which thrust tends to bend the free ends of the main blades forward and in the direction of flight.

By locating the bracing blades at the advancing side of the main blades with their entering edges 14, at one side but between the entering and trailing edges 15 and 17, respectively of the main blade, the bracing blade during revolution and being forward will operate on an air area different from that operated upon by the main blade and an increased thrust is exerted on the hub and driving shaft over that which the main blades alone would exert.

It is therefore to be understood that the bracing blades not only brace the main blades in both a lateral and a circumferential direction, but said bracing blades increase the thrust of the propeller and materially assist in driving the craft forward.

Having described my invention what I claim is:—

1. An air-craft propeller having a plurality of flat surfaced main blades, and a separate brace for each main blade, each brace having its outer end connected to the outer end of a main blade and its inner end secured in a trailing position with respect to the inner end of said main blade and in front of the next following main blade.

2. An air-craft propeller having a plurality of diametrically opposed main blades,

and a separate brace for each main blade, each brace extending between the hub-end and the outer end of a main blade and each brace also extending laterally and rearwardly with respect to the flat side of the main blade it braces and the inner end of each brace having position in front of the next following main blade.

3. An air-craft propeller having a plurality of main blades and a bracing blade for each main blade and each bracing blade having its outer end seated against the flat side of and bracing the outer end of a main blade and the inner end of each bracing blade being secured in a spaced and trailing relation with respect to the inner end of said main blade, and means for securing the outer ends of a main and a bracing blade together.

4. An air-craft propeller having a plurality of main blades and provided with a separate bracing blade for each main blade, each bracing blade having an entering edge at the forward side of the trailing edge of the main blade it braces and a trailing edge at the rear of the trailing edge of said main blade which it braces.

5. In an air-craft propeller the combination with a plurality of main blades, of a separate bracing blade for each main blade,—each bracing blade having a forward entering edge which through a greater portion of its length has position in a plane between the entering and trailing edges of the main blade it braces, means for securing the outer end of each bracing blade to the flat side and outer end of the main blade it braces, and means for securing the inner end of each bracing blade in spaced relation with respect to the hub-end of the main blade it braces.

6. An air-craft propeller having a plurality of straight main blades and an inclined bracing blade for each main blade, each bracing blade having its outer end seated against and secured to the outer end of a main blade and inclining laterally from said outer end toward the inner hub-end, and the inner hub-end of each bracing blade being secured in position at the rear of the trailing edge of the main blade it braces.

7. In an air-craft propeller, the combination with a plurality of straight main blades each having an entering edge, a trailing edge and an outer end, of a separate bracing blade for each main blade and each bracing blade having a flat surface with an entering edge, and a trailing edge which edges are located at opposite sides of the trailing edge of the main blade it braces,—the outer end of a bracing blade being secured at the side of the main blade it braces and the inner end of the same bracing blade projecting rearwardly and beyond the trailing edge of the main blade it braces, and being secured

at a spaced distance from the hub-end of the main blade whereby to form an inclined brace for the straight main blade.

8. An air-craft propeller having a plurality of main blades and each main blade having an inclined bracing blade at the side thereof, each bracing blade being shorter than the main blade and having its outer end secured against the flat side of the main

blade it braces and the inner end of each 10 shorter bracing blade extending rearwardly of the main blade it braces.

In testimony whereof I affix my signature in the presence of two witnesses.
